INVENTOR,

George L. Barrus,

BY

Frank E. Haskell
ATTORNEY.

UNITED STATES PATENT OFFICE

GEORGE L. BARRUS, OF GOSHEN, MASSACHUSETTS

SNOW FENCE

Application filed July 16, 1932. Serial No. 622,851.

This invention relates to improvements in the construction of snow fences of the type shown in Patent No. 1,773,128 issued to me on August 19, 1930 to which reference is made for a more detailed description of the snow fence shown herein. More specifically the present invention relates to a brace for a snow fence support and to the combination of such a brace with the support.

10 It is one of the objects of the invention to provide a brace which will hold the fence against forces tending to push it in a longitudinal direction.

It is also an object of the invention to 15 provide a brace of the character described which may be readily assembled in place with the support with which it is adapted to be used and which may be quickly and easily disassembled when the fence is taken 20 down.

It is a still further object of the invention to provide a simple, strong and readily fabricated brace which may be easily packed with the supports in a minimum space for 25 transportation and storage.

The foregoing and other objects of the invention will readily appear to those skilled in the art to which it appertains by a consideration of the following description 30 of one embodiment thereof taken in connection with the accompanying drawing in which

Fig. 1 is a perspective view of a complete fence showing fence supports, braces and 35 boards;

Fig. 2 is an enlarged perspective view of the upper portion of one of the supports with a brace in position;

Fig. 3 is an enlarged vertical section of the 40 upper portion of one of the supports with a brace in position; and

Fig. 4 is a side view of one of the braces.

Referring to the drawing more in detail a plurality of fence supports indicated generally by the reference character 10 sustain 45 a plurality of horizontally disposed boards 11. Each support comprises a pair of members 12 and 13 hingedly connected together at their upper ends as indicated at 14. The 50 lower ends of the members 12 and 13 are

preferably trimmed to provide each member with a pointed end 15 so that the support may be more readily driven into the ground. Each of the members 12 and 13 is provided with a plurality of rectangular openings 16 for the reception of the boards 11. The lower portion of each of these openings 16 is preferably tapering or wedge-shaped as indicated at 17 so that the weight 55 of the boards will hold them firmly in place. It is intended that the length of the boards shall be a little greater than the distance between supports and at each support there will be two boards extending in opposite 60 directions from the support and positioned side by side in the same opening. The width of the opening at its upper portion should be somewhat greater than the thickness of two boards and the width of the opening at the lower part of the wedge-shaped portion 17 65 of the opening should be somewhat less than two boards. It will be noted that the boards are shown in Fig. 1 as being all positioned 70 in the holes on the same side of the support instead of in the openings on alternate sides 75 of the supports as shown in the hereinbefore mentioned Patent No. 1,773,128.

At the lower end of each of the members 12 and 13 is shown an opening 22. This opening is provided so that an anchoring 80 stake 23 may be driven therethrough and into the ground in order to hold the support more firmly in position. It will be noted that the cross-section of the members 12 and 13 is Z-shaped, as more fully described 85 in my former patent, which permits the members to fold together readily for purposes of transportation and storage and at the same time provides great strength and 90 rigidity.

I preferably provide an aperture 18 at the upper end of each support which may be circular in form. As shown in my former patent this aperture may be a part of the hinge structure for a more detailed description 95 of which reference is made to the aforesaid patent.

The brace comprises a member 25 which is 100 preferably constructed of the same Z-shaped material as the members 12 and 13 and is

shown in detail in Figs. 2 to 4. As shown in the drawings the member 25 is provided with an upper flange 25a and a lower flange 25b. The upper end of the member 25 has 5 the flange removed and the web is reduced somewhat in size so that the overall dimension is less than the diameter of the aperture 18. The upper edge of the member 25 is notched near the end as indicated at 26 to 10 provide a shoulder 27 which is adapted to rest against the upper inside of the aperture 18 when the brace is in the inclined or bracing position as shown in Fig. 3. The lower edge of the member 25 is also notched 15 as indicated at 28 to provide a shoulder 29 adapted to rest against the lower outside of the aperture 18 as clearly shown in Fig. 3. In order to prevent the lower flange 20 of the member 25 from striking the brace in the inclined position, there also may be provided a notch 30 on the lower edge of the member 25. The lower end of the member 25 may be pointed as indicated at 15a and is preferably provided with an opening 25 22a for an anchoring stake 23a.

In assembling the fence the supports 10 and boards 11 are put in place and then with a brace 25 held in a substantially horizontal position the upper end is inserted 30 in the aperture 18 of one of the supports and the opposite end lowered until it rests against or is driven into the ground. The anchoring stake 23a is then driven through the opening 22a and assists in holding the brace in position. It will be noted that the shoulder 27 prevents the brace from moving outwardly from the aperture 18 and the shoulder 29 prevents the brace from moving inwardly with respect to the aperture 18. 35 Or stated conversely, the brace being firmly held in the hinge aperture, the upper end of the brace holds the hinge part of the support 10 from movement longitudinally of the fence as a whole in either direction. It 40 is not necessary that a brace be employed for every support as shown in Fig. 1, the number of braces recommended being from 10 to 16 per 100 supports depending upon the height of the fence.

50 It will be seen that there has been provided a simple, rugged, and inexpensive brace which is also easy to install and remove. Being of the same cross-sectional form as the members comprising the supports it will also "nest" with the folded supports for transportation or storage.

It is to be understood that the hereinbefore described embodiment of the invention is for the purpose of illustration only and 60 various changes may be made therein without departing from the spirit and scope of the invention as defined in the subjoined claims.

I claim:

65 1. In a snow fence, a fence support hav-

ing an aperture near the upper end thereof, and a brace having its upper end formed to enter said aperture when said brace is in one position relative to said support and to lock itself in said aperture when said brace is in another position relative to said support. 70

2. In a snow fence, a fence support having an aperture near the upper end thereof, and a brace having its upper end formed to enter said aperture when said brace is in a substantially horizontal position and to lock itself in said aperture against movement either inward or outward when said brace is in its inclined or bracing position. 75

3. In a snow fence, a fence support having an aperture near the upper end thereof, and a brace for said support, the upper end of said brace having a smaller overall dimension than said aperture when said brace is in a substantially horizontal position, and means associated with said brace for preventing withdrawal of said brace from said aperture when said brace is in an inclined or bracing position. 80

4. In a snow fence, a fence support having an aperture near the upper end thereof, and a brace for said support, the upper end of said brace having a smaller overall dimension than said aperture when said brace is in a substantially horizontal position, and shoulders on the end of said brace adapted to rest against the upper inside and lower outside of said aperture when said brace is in an inclined or bracing position. 85

5. In a snow fence having a fence support with a round aperture in the upper end thereof, a brace comprising a single integral piece formed of sheet metal, the upper end of said piece being reduced in size to pass 90 through said aperture when said brace is in a substantially horizontal position and having a notch cut in said reduced end to provide a shoulder to prevent withdrawal of said brace when in an inclined or bracing position. 100

6. In a snow fence having a fence support with a round aperture in the upper end thereof, a brace having a flat portion at the upper end thereof reduced in size to pass 115 through said aperture when said brace is in a substantially horizontal position, said reduced end portion having a notch cut in its upper edge to provide a shoulder to prevent withdrawal of said brace when the other end thereof is lowered into bracing position. 120

7. In a snow fence having a fence support with a round aperture in the upper end thereof, a brace having a flat portion at the upper end thereof reduced in size to pass 125 through said aperture when said brace is in a substantially horizontal position, said reduced end portion having a notch cut in its upper edge to provide a shoulder to prevent withdrawal of said brace when the other end 130

thereof is lowered into bracing position, said reduced end portion also having a notch cut in its lower edge to provide a shoulder to limit the inward movement of said brace into said aperture when the other end of said brace is lowered into bracing position.

8. A brace for a snow fence support comprising a web, two oppositely extending flanges giving the brace a Z-shaped cross-section, an end portion having the flanges removed and the web reduced in width, a shoulder formed on the upper edge of said end portion adapted to prevent movement of said brace in one direction, and another shoulder on the lower edge of said brace adapted to prevent movement of said brace in the opposite direction.

9. In a snow fence, a pair of members hingedly connected together at their upper ends, said hinge structure providing an aperture therethrough, and a third member having its upper end detachably engaging said pair of members at the aperture and having its lower end resting against the ground.

In testimony whereof, I affix my signature.

GEORGE L. BARRUS.
